FAUCET SPRAY-AERATOR

Donald W. Doman, Janesville, Wis., assignor to
Kohler Co., Kohler, Wis.

Filed Aug. 3, 1972, Ser. No. 277,798

Term of patent 14 years

Int. Cl. D23—01

U.S. Cl. D23—35

FIG. 1 is a side view in elevation of a faucet spray-aerator showing my new design, the fragmentary broken line representation of a faucet spout being for illustrative purposes only;

FIG. 2 is a top plan view thereof;

FIG. 3 is a bottom plan view thereof;

FIG. 4 is a cross-sectional view taken on line 4—4 of FIG. 1.

I claim:

The ornamental design for a faucet spray-aerator, as shown and described.
